UNITED STATES PATENT OFFICE

GEORGE ELTON RICE, OF BROOKLYN, NEW YORK, ASSIGNOR, BY DIRECT AND MESNE ASSIGNMENTS, TO CONSERVATION CORPORATION OF AMERICA, A CORPORATION OF DELAWARE

PROCESS FOR TREATING, IMPREGNATING, SEASONING, AND STABILIZING WOOD

No Drawing.

Application filed April 8, 1925. Serial No. 21,695.

The present invention relates to processes for treating, impregnating, seasoning and stabilizing wood, and is particularly an improvement over the processes disclosed in my copending applications Serial Nos. 726,834 and 735,218, filed July 18 and Aug. 30, 1924, respectively.

One of the objects of the invention is to treat the wood with a solution that removes the extraneous matters from the wood, such as fats, starches, sugars, gums, acids, oils, dyes, resins, tannins, albumen, etc., and which will simultaneously dehydrate the wood so as to reduce the moisture content of the treated wood to the minimum, without requiring artificial or kiln drying.

Another object is the treatment of the wood to remove the extraneous matter, including moisture, and to simultaneously saturate or impregnate the wood with waterproofing and dehydrating material, so that the treated wood will be waterproof, dry and ready for use in a short time after treatment.

A further object is the treatment of the wood with such materials as to eliminate the extraneous matters from the wood and to simultaneously impregnate the wood with a material or substance that will preserve and waterproof the wood as well as enabling the wood to take paints, varnishes and other finishing materials readily and advantageously.

The invention also has for an object to combine in a single operation the removal of the extraneous matters from the wood, and the replacement thereof by the preserving and protecting material or substance.

The treatment of the wood with this process also includes the protection of the wood from fungi, rot, insects, and the like.

The solution used for the treatment of the wood, contrary to the solutions as disclosed in the aforesaid copending applications, is non-aqueous, in that it contains no water, thereby not only assisting materially in driving the water or moisture from the wood, but also eliminating both the saturation of the wood by water in the solution and the requirement for subsequent artificial drying. In this way, two advantages are obtained at the same time, namely, the driving out of the

natural moisture from the wood, and the elimination of the entry of moisture from the solution into the wood during treatment. The dehydration of the wood can therefore be made more thorough, and may be regulated.

The solution contains sugar of saccharine matter to obtain the advantages thereof in expelling the foreign matters from the wood, and the solution also contains a suitable oil, whereby the sugar and oil simultaneously impregnate the wood to eliminate the extraneous matter therefrom and to dehydrate the wood, and at the same time to protect and preserve the wood for subsequent use.

The proportions of the constituents of the solution may vary, for different woods, and as an example for freshly felled or partly air dried maple, birch or sweet gum, ash, mahogany, and similar woods, the solution will comprise the following:

	Pounds
Linseed oil	1000
Sugar	150
Sodium fluoride	35
Sodium sulphate	15

The proportion of the sugar is substantially 15%, by weight, of the amount of oil, and the proportions of sodium fluoride, and sodium sulphate are substantially 3½ and 1½ percents, respectively, of the amount of the oil. The linseed oil used is heat treated to fix the "foots" or gummy content. The saccharine matter or sugar component of the solution may be equal parts of maltose and cane syrup or molasses. Malt sugar and cane sugar (granulated or brown) may be used in place of maltose and the syrup. A sweet potato syrup may also be used in lieu of cane products when available.

Although linseed oil is mentioned, other drying vegetable oils may be used, such as tung, perilla, soya bean, and similar vegetable oils, or combinations thereof.

The ingredients are mixed at a temperature varying from 100 to 120 degrees F., the oil being heated to such temperature and the saccharine and other materials then being added to and mixed with the oil.

The wood may be treated in any shape or

form, either timber, lumber or wood products, and timber may be treated with or without the bark being removed. The term "wood" also includes vegetable fibres for which the process is suitable.

5 The wood is immersed in the solution, and this can be done in several different ways, such as by loading the wood in piles or stacks in or on a rack or flat truck, skid or other 10 conveyance, which is run into a tank, or the wood may be conveyed into the tank by an overhead or automatic conveyor, or may be piled or stacked in the tank. If the wood is lowered into and elevated from the tank, then 15 the sides and ends of the tank may be solid, but if the wood is conveyed on tracks into and out of the tank, the ends of the tank are arranged to open for the entrance and exit of the conveyors or vehicles carrying the 20 wood. An open rectangular tank is preferably used, although it is preferable to provide a hood or cover for the tank to confine the vapors so that they can be drawn off and 25 conserved for the recovery of valuable by-products.

After the wood is placed in the tank and held therein so as not to float to the top of the solution, the solution is delivered into the tank to fill the tank to a level several inches above 30 the wood. The solution is heated, such as by submerged steam radiators at the bottom of the tank, until the solution reaches a temperature of 130 degrees F. and is maintained at such temperature for about one hour, and 35 then gradually raised to between 210 and 212 degrees F. and maintained at such temperature until no further excess matters are seen leaving the wood. Then, after a period varying from one hour to several hours, based on 40 the thickness and density of the wood, the heat is shut off, and the wood and solution allowed to cool until no further bubbles are observed leaving the wood. The wood is then removed from the solution or allowed to 45 remain in the solution while it cools until the wood has become completely impregnated with the solution, and the impregnation may be regulated by the length of time the wood is permitted to remain in the cooled 50 solution. The impregnation may thus be varied according to requirements.

During the impregnation period, when especially dry wood is required, the wood is allowed to remain in the solution after the 55 initial heating and cooling, and the heat is then gradually raised a second time until it has reached a temperature between 214 and 230 degrees F., depending on the circumstances, and such temperature is maintained 60 until no further moisture bubbles leave the wood. The heat is then shut off and the solution pumped from the tank, after which the wood is removed, or, if desired, a second cooling period is provided to reduce the temperature down to between 160 to 100 degrees F.

according to the amount of impregnation of the waterproofing material desired, based on requirements.

As soon as the wood is removed from the solution, the tank and solution are ready for 70 the next load of wood.

During the treatment of the wood to the solution, the temperature of the solution being raised to or above the boiling point of water, will drive out the moisture from the wood, which passes off as vapor and discharges from the wood in bubbles that rise to the surface of the solution. Then, the cooling of the solution results in the solution being drawn into the wood so that the longer the cooling action takes place the greater will be the impregnation of the wood, and the heating and cooling periods may be repeated as indicated. The lengths of the heating and cooling periods are determined by the nature 75 of the wood being treated and results desired.

During the treatment or boiling of the immersed lumber, the solution penetrates the wood, and owing to osmotic action the solution acts under pressure from all sides in the wood, and a steady stream of extraneous matters are expelled from the wood until the wood is cleansed. The wood is also sterilized, the poison being combined with the fibres and interstices, and the crystals of the poison remain in combination with the fibres and interstices and have reserve power so that they 90 constantly expel toxic poison for indefinite periods. The poison prevents further action of fungus or wood destroyers and avoids the liability of dry rot occurring.

The fats, starches, sugars, gums, acids, oils, dyes, resins, tannins, albumen and other extraneous matters are removed from the wood in a simple, practical, and efficient manner, and are replaced by the solution or material that preserves and compacts the fibres; reducing the cell spaces, and filling the wood with the oil which waterproofs the wood as well as encapsulating in the fibre and cell walls the toxic poison that inhibits the wood against the attacks of wood destroyers, dry rot and other fungus.

Freshly felled or green timber as well as partly air dried timber or lumber may be seasoned rapidly by the present process, as well as being insect-proofed and waterproofed at the same time, in a single operation, without resorting to artificial driers. The linseed or other vegetable drying oil will waterproof and dehydrate the wood, as well as serving to encapsulate the toxic poison and retain same in the wood indefinitely. By timing the length of treatment or immersion of the wood it is possible to reduce the moisture content of the wood to a desired percentage, without requiring subsequent kiln or artificial drying, it being noted that the solution contains no water so that as the moisture is forced from the 105 110 115 120 125 130

wood by osmosis and heat, it is replaced by the elements of the solution, thereby obtaining the dehydration of the wood as well as the simultaneous impregnation thereof with the preservatives and protection ingredients of the solution. The cell walls, spaces and interstices of the wood are stabilized, sterilized and filled with the solution, and the oil not only water-proofs and dehydrates the wood, but also enables the surface of the wood to readily receive paints, varnishes and other finishing materials to advantage, inasmuch as the wood when impregnated with the oil will have a perfect affinity for practically all finishing materials. Furthermore, there is a saving in the amount of finishing material necessary, inasmuch as the absorption of the finishing materials by the wood is reduced, although the finishing material adheres effectively to the superficial portion of the wood.

When treating the wood the substances extracted from the wood are recovered in order to obtain valuable by-products. These are obtained from the scum rising to the surface of the solution which is skimmed off, and also from vapors passing from the solution which are drawn off and condensed. The treatment eliminates the extraneous matter from the wood without fracturing the cell walls or fibres, thereby reducing season checking and degrading. During the treatment, the cell walls are swollen, releasing the air combined with the fibres and cell walls, without breaking down the cell walls, and the spongy or soft portions as well as the summer or immature growth of the wood are filled, and the absorption properties of the wood equalized. The saccharine solution containing maltose and cane syrup or molasses products has been found to be especially effective, the maltose, which is fundamental monosaccharose, being strongly dextro-rotary and having greater osmotic action than dextrose or dextrin. The maltose forms a phenyl ozazole combined with the syrup or molasses (cane or beet) or neutral sugar, which is of advantage in carrying out the process and in the results obtained.

By combining the oil with the sugar or saccharine matter, this will enable the entire process to be carried out with a single treatment of the wood, eliminating water or moisture from the solution, so that the wood is simultaneously cured, cleansed, poisoned, dehydrated and waterproofed. The toxic poison combined with the solution will also prevent fermentation of the solution when not being used, and the poison being encapsulated by the oil in the treated wood will be prevented from being liberated too freely, thereby keeping the poison encapsulated or imprisoned to indefinitely repel destructive organisms and fungi and inhibit the

wood against future attacks from wood destroying insects, fungi and the like, as well as preventing moisture from entering the wood, which if it occurs, may cause the wood to shrink or swell, or to rot. The vegetable oil, or a combination of vegetable oils, such as hereinbefore mentioned, will also assist in removing the excess matters from the wood, as well as stabilizing the wood. The oil renders the wood a non-conductor of electrical energy so that the wood may be used for electrical insulating purposes. The oil also assists in preventing the warping or shrinking of the wood.

The process is based on the underlying natural laws that all colloidal substances, of which wood is the most important, absorb their similars, and that all colloidal substances become stable after being raised to a degree of heat substantially peculiar to each of them, from which it results, that in carrying out this process, the solution which is absorbed by the wood will be thoroughly assimilated by the tissues and held in combination with the fibres of the wood and in the interstices, and no matter how hard the wood is it will be cleansed of extraneous matters, and the live, summer or sap wood stabilized to equal the heart or fixed growth of the wood, without the aid of vacuum or pressure equipment in the treatment required. The process is a natural one, under atmospheric pressure, being the action of a similar on a similar, and as the wood is impregnated by capillary and osmotic action, the excess matters removed are replaced by the material with which the wood is impregnated which will dry and oxidize slowly in combination with the fibres, interstices and cell walls, and the cells may be completely filled when required.

Having thus described the invention, what is claimed as new is:—

1. The process of cleansing, dehydrating and impregnating wood consisting in impregnating wood with a non-aqueous saccharine solution.

2. The process of cleansing, dehydrating and impregnating wood consisting in impregnating wood with a non-aqueous saccharine solution heated to or above the boiling point of water.

3. The process of cleansing, dehydrating and impregnating wood consisting in immersing wood in a non-aqueous saccharine solution.

4. The process of cleansing, dehydrating and impregnating wood consisting in immersing wood in a non-aqueous saccharine solution heated to or above the boiling point of water.

5. The process of cleansing, dehydrating and impregnating wood consisting in simultaneously impregnating wood with oil and sugar.

6. The process of cleansing, dehydrating

and impregnating wood consisting in simultaneously impregnating wood with oil and sugar heated to or above the boiling point of water.

- 5 7. The process of cleansing, dehydrating and impregnating wood consisting in immersing wood in a mixture of oil and sugar.
8. The process of cleansing, dehydrating and impregnating wood consisting in immersing wood in a mixture of oil and sugar heated to or above the boiling point of water.
- 10 9. The process of cleansing, dehydrating and impregnating wood consisting in simultaneously impregnating wood with sugar and vegetable oil.
- 15 10. The process of cleansing, dehydrating and impregnating wood consisting in simultaneously impregnating wood with sugar and vegetable oil heated to or above the boiling point of water.
- 20 11. The process of cleansing, dehydrating and impregnating wood consisting in immersing wood in a mixture of sugar and vegetable oil.
- 25 12. The process of cleansing, dehydrating and impregnating wood consisting in immersing wood in a mixture of sugar and vegetable oil heated to or above the boiling point of water.
- 30 13. The process of cleansing, dehydrating and impregnating wood consisting in immersing wood in an oil-saccharine mixture, heating the mixture to or above the boiling point of water, and then cooling the mixture before removing the wood.
- 35 14. The process of cleansing, dehydrating and impregnating wood consisting in immersing wood in a mixture of vegetable oil and sugar, raising the temperature of the mixture to or above the boiling point of water, and then permitting the mixture to cool before removing the wood.

In testimony whereof I hereunto affix my signature.
